AEROPLANE CONTROL

George A. Clark, Filer, Idaho

Application June 2, 1936, Serial No. 83,095

1 Claim. (Cl. 244—83)

This invention relates to improvements in aeroplane control and the object of the invention is to simplify the controlling of the rudder, elevator, and ailerons of an aeroplane.

5 In accordance with the present invention the rudders, elevators and ailerons are controlled from a single stick to the end that the aeroplane will be always under the direct control of the operator thus rendering it more safe for student 10 flyers as well as for experienced airmen.

The invention together with its objects and 15 advantages will be best understood from a study of the following description taken in connection with the accompanying drawing wherein the single view illustrates diagrammatically the improved aeroplane control embodying the features of the present invention.

20 Referring to the drawing by reference numerals it will be seen that the numerals 5 indicate the ailerons of an aeroplane, while the elevators are indicated by the reference numerals 6 and the rudder by the reference numeral 7. The elements mentioned are mounted on the aircraft in the usual manner.

25 In accordance with the present invention there is suitably mounted within the pilot's cabin of the aeroplane a rock shaft 8 provided with a single control stick 9.

30 Shaft 8 at the respective opposite ends thereof is provided with crank arms 10 in the form of plates there being one crank arm 10 for each elevator 6.

35 The upper end of each crank arm 10 is connected through the medium of a cable 11 and a depending lug 12 on the underside of its aileron 5 with said aileron 5, while the lower end of each crank arm 10 is connected through the medium of a cable 13 and a lug 14 rising from the top surface of the elevator 6, with said elevator 6. It will thus be seen that by working the lever 9 back and forth the elevators 6 may be raised or lowered as found desirable for the proper control 40 of the aeroplane.

45 Also the ailerons 5 are provided on their top sides with upstanding lugs 15 to which are connected the relatively opposite ends of a cable 16 trained over suitably arranged pulleys 17. The ailerons 5 have depending from the undersides thereof lugs 18 to which are connected one end of cables 19 each of which at its respective opposite end is connected to a laterally extending plate or arm 20 suitably mounted on the stick 9. Cables 19 are also trained over suitably arranged pulleys 21. Thus it will be seen that by rocking the stick 9 either forwardly or backwardly the ailerons 5 will be elevated or lowered as found desirable and simultaneously with the elevating or lowering of the elevators 6.

55 The rudder 7 also has projecting from opposite sides thereof lugs 22 to which are connected one

end of cables 23. Cables 23 cross one another and each is secured at its respective opposite end to a laterally extending plate or arm 24 secured on the stick 9 below the plate 20. Cables 23 are also trained over suitably located pulleys 5

25. Thus by rocking the stick 9 laterally either to the right or left the elevator 6 will be swung either to the right or left for effecting a change in the path of travel of the aeroplane either to the right or left.

10 In connection with the above it will be understood, and as shown, that the stick 9 is pivoted at one end as at 25 to the shaft 8 so that the stick 9 may be swung laterally either to the right or left for operating the rudder 7 and for raising 15 one of the ailerons 5 while at the same time the other of the ailerons 5 is lowered. Thus in this connection it will be noted that the ailerons 5 may be either raised or lowered simultaneously or one of the ailerons may be raised while the other is 20 being lowered.

25 From the above it will be seen that the control elements of an aeroplane, namely the rudder, elevators, and ailerons may be all operated from a single control stick thus simplifying to a great degree the control of an aeroplane. Accordingly, in addition to the safety feature thereof my improved aeroplane control will be found especially useful in the training of pilots as it will reduce considerably the time now generally required for the novice to become efficient in the handling 30 of the control elements of an aeroplane.

35 Having thus described the invention what is claimed as new is:—

40 In a control mechanism for aeroplanes, a shaft rotatably journaled in the fuselage of an aeroplane transversely thereof, a control stick pivoted to the shaft for independent transverse movement, said stick being also operable to rotate the shaft upon a forward and rearward movement of the stick, rocker arms on the respective opposite ends of the shaft, a pair of elevator control wires secured at one end to the respective opposite end 45 of each of the rocker arms, a plate member secured on said control stick, a pair of aileron control wires secured at one end to said plate at opposite sides of the control stick and connected to the ailerons of the aeroplane, a second plate secured to the control stick adjacent the first named plate, and control wires secured at one end to the respective opposite ends of the second named plate at opposite sides of the control stick and connected to the rudder of the aeroplane for simultaneously actuating the rudder and ailerons, a control wire and laterally spaced pulleys adjacent said ailerons, said control wire being trained over said laterally spaced pulleys and connected at its respective opposite ends with the ailerons for transmitting movement of one aileron to the other.

50 GEORGE A. CLARK. 60
